COLLAPSIBLE WARDROBE

Abraham Stone, Brooklyn, N. Y.

Application May 2, 1935, Serial No. 19,333

2 Claims. (Cl. 312—144)

This invention relates to containers and has particular reference to a multi-compartment container which is designed to serve as a wardrobe for the storage of clothing in order to protect the same from moths, dust or other harmful agencies.

The invention comprehends in a container of the indicated character, a body section having a partition formed integral with the rear wall thereof and which partition subdivides the container into laterally spaced compartments, and cover and base sections interfitted with the upper and lower ends of the body section and preferably having means for holding the partition in fixed position.

The invention further includes a body section constructed of comparative light weight stock and which comprises hingedly connected side and rear walls, a partition formed integrally with the rear wall and sub-dividing the container into compartments and closures for the compartments swingably connected with the side walls, the construction being such as to permit of the folding and collapsing of the body section to a flat compact arrangement for shipment and storage.

More specifically the invention comprises a container including an integral body section which is scored and bent to provide side and rear walls, a partition sub-dividing the container into laterally spaced compartments and closures for the compartments, and cover and base sections telescopically interfitted over the upper and lower ends of the body section for securing the body section in set up condition.

The invention further provides a ball carried by the cover section for holding the partition in fixed position and providing a means for suspending clothing on hangers in the compartments.

With these and other objects in view, the invention is shown in the accompanying drawing in which there is disclosed a preferred form thereof, while the appended claims cover variations and modifications which fall within their scope.

In the drawing:

Fig. 1 is a vertical sectional view taken approximately on the line 1—1 of Fig. 2, of a container embodying the invention.

Fig. 2 is a vertical sectional view thereof taken approximately on line 2—2 of Fig. 1.

Fig. 3 is a horizontal sectional view taken approximately on line 3—3 of Fig. 1.

Fig. 4 is an end view of the body section in partly collapsed condition.

Referring to the drawing by characters of reference, A designates generally the main body section of the container or wardrobe, which section is preferably constructed from a single sheet of cardboard, corrugated paper board or other light weight stock and includes a rear wall 10, side walls 11 and 12 swingably connected to the rear wall and closures 13 and 14 swingably connected to the side walls respectively and provided with flaps 15 and 16 swingably connected to the vertical free edges thereof.

The rear wall 10 has an integral intermediate portion which is doubled medially upon itself to provide a vertically extending forwardly projecting double ply wall 17 forming a partition which subdivides the container into laterally spaced compartments. The remaining portions of the rear wall 10 are swingable with reference to the wall or partition 17, from a right angularly disposed set up position to a collapsed position substantially in the plane of said wall or partition so that when the body section is collapsed the walls, partition and closures are disposed in a flat compact arrangement for storage and shipment as shown in Fig. 4 of the drawing. The forward free vertical edge of the wall or partition 17 is embraced by a channeled reinforcing strip 18 which serves as a parting strip against which the flaps 15 and 16 impinge to seal the closures, and the plies of the wall or partition adjacent their juncture with the rear wall are preferably secured together by fastening elements 19.

The container also includes base and cover sections B and C which are substantially identical in construction and which engage the opposite end portions of the body section A for holding the body section in set up condition and are designed to be assembled with the body section to provide the container or wardrobe, or disassembled for nesting the same with the collapsed body section.

As illustrated, the base and cover sections each includes a panel 20 having a marginal flange 21 which flanges of the said sections are telescopically fitted over the opposite ends of the body section, the upper and lower ends of the body section having inwardly extending slots 22 at 50 the juncture of the side walls with the closures to receive the flanges 21. The cover section C is provided with a ball 23 preferably swingably connected to the underside of the panel 20 and provided with a medial upwardly offset bight 24 of 55

a proper size to snugly receive the upper end portion of the wall or partition 17 for holding the partition in its set up condition parallel to the side walls 11 and 12. The bail also serves as a support for garment hangers to be suspended therefrom.

The base and cover sections may be secured in position on the body section A by fastening elements 25 which engage through registering apertures 26 in the body section A and in the flanges 21 of the base and cover sections.

What is claimed is:

1. In a collapsible container, a body section including a rear wall having a forwardly extending partition adapted when the container is set up to subdivide the same into laterally spaced compartments, side walls swingably connected to the rear wall and closures for the compartments swingably connected to the side walls, said walls, partition and closures being foldable so as to permit of the complete collapsement of the section to flat compact arrangement, cover and base sections interfitted with the upper and lower ends of the body section for holding the body section in set up condition, and a bail swingably connected at its opposite ends with the cover section and provided with a medial upwardly offset portion defining parallel arms clampingly engaging over the upper end of the partition for holding the same in compartment-forming position and said bail providing horizontally disposed sup-

porting portions within each compartment for suspending garments within the compartment.

2. In a collapsible container, a body section including a rear wall having swingably connected portions and an intermediate portion doubled upon itself to provide a vertically extending forwardly projecting two ply partition adapted to subdivide the container into compartments, side walls formed integral with the side edges of the rear wall portions and swingably associated therewith, and closures for the compartments formed integral with the side walls and swingably associated therewith, said walls, partition and closures being foldable so as to permit the complete collapsing of the section to flat compact arrangement, with the rear wall portions in alignment with the plies of the partition and with the side walls and closures in parallel relation thereto and covering the same, cover and base sections interfitted with the upper and lower ends of the body section, and a depending bail swingably connected at its opposite ends with the cover section and provided with a medial upwardly offset portion defining parallel arms clampingly engaging over the partition for holding the same in compartment-forming position and said bail providing horizontally disposed supporting portions within each compartment for suspending garments therein.
